(57) **CLAIM**

The ornamental design for a display screen portion with icon,
as shown and described.

DESCRIPTION

FIG. 1 is a front view of a display screen portion with icon
showing my new design; and,

FIG. 2 is a front view of a display screen portion with icon of
FIG. 1, in which a mobile terminal in broken lines is provided
to illustrate an example environment.

The broken line drawing of the mobile terminal, and the
numbers, symbols and otherwise images shown in broken
lines in FIGS. 1 and 2 are for illustrative purposes only and
form no part of the claimed design.

1 Claim, 2 Drawing Sheets

FIG. 1

FIG. 2
